CURTAIN FIXTURE

Charles J. De Muth, Boston, Mass., assignor to
William J. McDonald, Malden, Mass.

Application March 24, 1938, Serial No. 197,819

3. Claims. (Cl. 156—22)

This invention relates to improvements in curtain fixtures. More particularly it relates to an improved bracket and rod structure and assembly for hanging window curtains and drapes, and providing for swing of each curtain section and drape section, independently of each other, toward and away from the window.

10 Curtain fixtures as heretofore proposed, for permitting independent swinging adjustment of the curtain sections and of overdrapé sections, have involved the use of intricate and cumbersome brackets which have been generally unsatisfactory as well as being impractically expensive to manufacture.

15 The present invention has among its objects to provide a curtain and drape fixture wherein a separate extensible and contractible rod is provided for each curtain section and for each drape section, all mounted, for individual swinging, in
20 a pair of brackets which conveniently and economically may be stamped from sheet metal.

Another object is to effectively coordinate a curtain rod and a drape rod in each bracket with the drape rod maintained at a desired higher level than the curtain rod.

A further object is to provide simple yet effective means at the free end of each rod, for maintaining its curtain or drape against slipping from the rod.

30 A feature resides in the bracket structure which permits each bracket to serve either on the right side or the left side of a window casing.

It is, moreover, an important feature that my improved fixture, while providing for effective arrangement of the drapes around the brackets, contributes to a generally pleasing aesthetic treatment.

The mentioned objects and results may be attained with a bracket structure having a U-portion within which one end of a curtain rod may be hingedly mounted, and upon which one end of a drape rod may be hingedly mounted, each said rod being movable about its hinge, from a normal position where it may extend approximately parallel to the window casing, outward through at least 90°.

The bracket conveniently and economically may be stamped from suitably stiff sheet metal, and it is a feature of importance that the brackets of each pair may be identical in form and structure so that either may be used on the right side of a window casing, and either may be used on the left side by merely inverting that one relative to the other.

5 Both the curtain rod and the drape rod for each

bracket may be extensible and contractible, to fit various sizes of windows; and each rod, at its free end, has means preventing slipping of curtain or drapes from the rod.

The rods are readily removable from a bracket by merely lifting out a hinge bolt in the one, and by merely lifting the other bodily from the bracket.

Only relatively small projection of the brackets, from the casing outward, is needed; and this projecting part may be further utilized for securing a drape in an attractive manner, to cover and obscure the brackets. However, the brackets, when left visible, are of design to contribute to a generally attractive aesthetic window treatment.

It is intended that the patent shall cover, by suitable expression in the appended claims, whatever features of patentable novelty exist in the invention disclosed.

In the accompanying drawing:

Figure 1 is a perspective of the upper portion of a window casing equipped with fixtures embodying features of the invention;

Figure 2 is a perspective of one of the brackets of Figure 1, greatly enlarged, and showing the curtain and drape rods mounted therein, a mid-portion of each rod being broken away; and

Figure 3 is a side elevation of the bracket of Figure 2, looking from the right in Figure 2, the rods being shown in section.

Referring to the drawing, a pair of brackets 10, 12, one at each side of the window, high on the window casing 14, pivotally support the curtain rods 16, 18 and the drape rods 20, 22, so that each rod may swing toward and away from the window.

The brackets 10, 12 each has a generally U form, but in use they are disposed with the mouth 24 of each U toward the window casing, and with the bridge 26 of each U spaced outward from and parallel to the plane of the casing. As represented, the space between the U-arms 28, 30 corresponds approximately to the breadth of the cur-

tain rod 16, so that the cylindrical end portion 32 of the rod can fit upright within the U. The U-arms may extend in parallelism at right angles to the plane of casing 14 but, as represented they depart from parallelism a little inward of the desired location of the curtain rod, extending thence obliquely toward the casing as at 42, 44, 50 each arm terminating in a foot 46. The cylinder 32 of rod 16 preferably is located between the innermost parallel portions of the U-arms, close to their inner edges, and may be secured by merely dropping a bolt 34 through hole 36 in arm 28.

hole 38 in the cylinder and hole 40 in arm 30. With this simple construction, rod 16 has a firm pivotal bearing in the bracket, yet may be readily and quickly removed by merely lifting out bolt 34.

Forward of the curtain rod bearing, the U-form of the bracket has less breadth of metal, so that the curtain rod 16 can swing through 90° from its normal position of parallelism with casing 14.

10. Each curtain rod 16, 18 preferably consists of the telescoping sections 16, 16' or 18, 18' whereby it readily may be adjusted as to length. And the free end of each has at the front face of the rod, an overlying tongue 36 within which the curtain engages, and by which the curtain is prevented from slipping from the rod.

Whereas the curtain rods 16, 18 may have the broad, flat shape as illustrated, the drape rods 20, 22 preferably have approximately square cross-section, being telescopically constructed of the parts 20, 20' and 22, 22' for adjustment as to length. And each may have in its free end an ornamental plug-retainer 48 for holding a drape on the rod.

25. The bracket end of each bar 20, 22 is bent through 90° relative to the main body, and this bent end, 50 or 52 sticks down through the forward, vertically aligned round holes 54, 56, respectively in the U-arms 28 and 30. Each rod 20, 22, is thus hingedly retained in a horizontal plane, with ability to swing inward to parallelism with casing 14, and outward as far as may be desired, even to the extent of being parallel with the wall on the outer side of the bracket.

35. Slidable pin or clip holders 60 may be strung on the rods 20, 22, for suspension of drapes. And one or more holes 62 in the U-arm which happens to be uppermost provides for securing the drape attractively around the bracket.

40. It is a feature of the invention that the brackets 19, 12 may be identical in structure and in form, each being adapted for serving at the right or the left side of the window by mere inversion of the bracket at one or the other location. Therefore the bracket of Figures 2 and 3 which show a structure and arrangement for the left side of a window, would be the same but inverted for the right side.

I claim as my invention:

50. 1. A curtain rod fixture comprising a U-form bracket having feet for mounting the bracket with

the mouth of the U toward the mounting surface; a curtain rod having one end portion formed as a bearing for fitting between the arms of said U-body; a forward portion of the U-body being reduced substantially in breadth by removal of 5 metal from one side edge; there being aligned holes through the arms of the U rearward at a location of greater breadth of U-body and close to that side edge from which metal was removed; and there being a hole through said bearing portion of the rod for registering with said aligned holes; and a hinge pin inserted through all of said holes.

2. A curtain rod fixture comprising a U-form bracket having feet for mounting the bracket 15 with the mouth of the U toward the mounting surface; a curtain rod having one end portion formed as a bearing for fitting between the arms of said U-body; and a drape rod having one end portion bent approximately at a right angle to 20 the main portion of the rod and extending through aligned holes in the arms of the U, adjacent to the bridge of the U, with the rod hingedly supported on and having a bearing on the upper arm of the U; the forward portion of the U-body 25 at which said drape rod is mounted being reduced in breadth by removal of metal from one side edge; and said bearing portion of the curtain rod being hingedly mounted between the arms of the U at a rearward location of greater breadth of U- 30 body, and close to that side edge from which metal was removed.

3. A window-frame fixture comprising a U-form bracket adapted to be mounted on a window frame with the mouth of the U toward the casing and with the arms of the U disposed one above the other, said bracket having substantially less breadth at the bridge of the U than at the mouth of the U, combined with a curtain rod pivotally mounted at one end between the arms of the U 40 at a location adjacent to the mouth of the U and offset sidewise with respect to an edge of the bridge of the U; and a drape rod pivotally mounted on and above the upper arm of the U at a location adjacent to the bridge of the U; both of 45 said rods being straight from the axes of their mounts to the tips of their free ends, and each being swingable independently of the other through at least 90° from parallelism with said casing.

CHARLES J. DE MUTH. 50
